UNITED STATES PATENT OFFICE.

WILBURN N. DENNISON, OF MERCHANTVILLE, NEW JERSEY, ASSIGNOR TO VICTOR
TALKING MACHINE COMPANY, A CORPORATION OF NEW JERSEY.

CUTTER FOR REPRODUCING-STYLI.

1,050,815.

Specification of Letters Patent.

Patented Jan. 21, 1913.

Application filed June 16, 1911. Serial No. 633,513.

To all whom it may concern:

Be it known that I, WILBURN N. DENNISON, a citizen of the United States, and a resident of the borough of Merchantville, county of Camden, and State of New Jersey, have invented certain new and useful Improvements in Cutters for Reproducing-Styli, of which the following is a specification, reference being had to the accompanying drawings.

The main objects of this invention are to provide a simple and efficient device for cutting or re-sharpening sound reproducing styli, particularly styli made of vegetable fiber, or other similar material; to provide in a cutter an improved adjustable cutting blade, and improved means for holding a stylus in position to be acted upon by the blade; and to provide other improvements as will appear hereinafter.

In the accompanying drawings, Figure 1 is a front elevation of a cutter constructed in accordance with this invention; Fig. 2 a top plan view of the same; Fig. 3 a rear elevation of the same; Fig. 4 an enlarged fragmentary perspective of a portion of the same; Fig. 5 a plan view of a detail of the same; Fig. 6 an enlarged perspective of a stylus; and Fig. 7 a fragmentary sectional view on line 7—7 of Fig. 3.

Referring to the drawings, one embodiment of this invention comprises a flat rigid base 1 projecting upwardly from which, and integral or rigid therewith, is a standard 2. To the upper end of the standard 2 is pivoted a blade lever 3 to reciprocate in a vertical plane, and secured to this lever is a flat vertical blade 4, which reciprocates against a flat vertical shearing plate 5, the lower portion of which is rigidly secured by screws 6 or other suitable means to a feed block or support 7 integral or rigid with the base 1. The free end of the lever 3 is provided with a thumb piece 8 rigid therewith for the convenient operation of the lever. For pivotally connecting the blade lever 3 to the standard 2, the upper portion of the standard is provided with oppositely disposed coaxial cylindrical bosses 10 and 11 projecting laterally in opposite directions therefrom and integral or rigid therewith. A

horizontal cylindrical aperture 12 extends through the upper portion of the standard and its bosses 10 and 11 coaxial therewith and forms a bearing in which snugly or rigidly engages a pivot 13, the outer end of which is provided with a slotted head 14 which engages against the adjacent end surface of the outer boss 10. The inner end of the pivot 13 projects beyond the inner boss 11 and is reduced in diameter as at 15 to form an annular shoulder 16 just outside of the inner boss 11, and is threaded into the blade lever 3, the shoulder 16 being turned up tightly against the adjacent face of the blade lever to hold the pivot rigid with respect to the blade lever so that as the blade lever oscillates, the pivot will rock in its bearing.

The blade 4 may be of any well known or suitable construction, but is preferably in the form of a flat tempered steel plate bounded by a plurality of sharp cutting edges 20 forming a regular polygon, in this instance a hexagon, the cutting edges being formed by beveling the margin of the blade only upon the side of the blade that is not in contact with the shearing plate. The blade is preferably pivoted upon a screw 21, which extends loosely through an aperture 22 provided therefor in the central portion of the blade. The inner end of the screw is threaded through the blade lever and the outer end of the screw is provided with a head 23 which engages against the outer surface of the blade and clamps the blade rigidly against the blade lever to hold the blade fixed with respect to the lever. For adjusting the blade to bring any selected one of its cutting edges into operative position, the blade is preferably provided with a series of apertures 25 of equal diameters and corresponding in number to the number of the cutting edges and equispaced from and around the center of the central aperture 22, of the blade, and the blade lever 3 is provided with a threaded aperture 26 arranged to register consecutively with the apertures 25 of the blade as the blade is rotated about its axis. Through this aperture 26 is threaded, from the rear side of the lever, a screw 27, one end of which is provided with

2
a head 28 which engages snugly against the rear side of the lever and the other end, 28, of which is reduced to the inside diameter of the threads and fits snugly in any one 5 of the apertures 25 of the blade. The aperture 26 in the blade lever is preferably arranged vertically above the aperture 22 in the center of the blade and the apertures 25 in the blade are preferably arranged on 10 diameters extending through opposite vertices of the blade so that the active cutting edge of the blade will always be oblique to its line of motion to give an oblique shearing cut.

15 For holding a stylus during the cutting operation, the feed block 7 is provided upon its upper surface with a groove 30 extending obliquely entirely across the feed block, and rectangular or of any other suitable 20 shape in cross section. The bottom wall 31 of the groove 30 is preferably inclined downwardly toward the plane of the blade and the side walls 32 of the groove are preferably vertical and oblique to the plane of the 25 blade. This groove is adapted to hold a stylus 33 of fiber or other similar material triangular in cross section and having a reproducing point 34, such as is shown in Fig. 6, in position to be resharpened by 30 blade 4. The shearing plate 5 is preferably made of steel and is provided with an aperture 35 to permit adjustment of the screw 21 upon which the blade 4 is pivoted, and this aperture is extended to form a continuation of the inner end of the slot 30 for holding the stylus in position. The reproducing end of the stylus is, therefore, held in place during the cutting action by the 35 walls of the aperture 30 in the shearing plate. For positioning a stylus 33 longitudinally in the groove 30, the blade lever 3 is provided with a lug or stop 36 integral therewith, which has a forwardly offset lower portion having a front vertical surface 37 spaced slightly in the rear of the plane of the cutting edges of the blade and depending in the path of the stylus and arranged to engage against the reproducing 40 point 34 of the stylus when the blade lever 3 is in its uppermost position and the stylus 45 is in position to be sharpened or acted upon by the blade, and also preferably to be moved out of contact with the stylus as the blade lever descends and before the blade 50 engages the stylus. For limiting the oscillation of the blade lever 3, the shearing plate 5 is provided with a segmental slot 40, coaxial with the axis of oscillation of the lever, and a screw extends loosely through the slot 55 and is threaded into the lever. For holding 60 the blade 4 always snugly but yieldingly against the shearing plate 5, the inner end of the inner boss 11 of the standard 2 is reduced in diameter to form an annular shoul-

der 45 and a cylindrical bearing 46. Fitting loosely over this cylindrical bearing 46 and engaging against the shoulder 45 is a tempered steel or other resilient washer 47 in the form of a spider, having spring arms 48 integral therewith and projecting radially and forwardly therefrom. The free ends of the spring arms 48 normally press against the outer surface of a washer 49, preferably of fiber or other similar material, loosely surrounding the bearing 46 and the 70 inner surface 7 which is pressed by the spring arms of the spider against the outer surface of the blade lever 3, thus forcing the blade lever and the blade carried thereby, toward the shearing plate 5, and keeping 75 the inner surface of the blade always snugly in engagement with the outer surface of the shearing plate.

For receiving the chips or ends of the 80 styli that fall from the blade during the 85 operation of this device, a tray 50 may be secured upon the base 1 in a suitable position below the blade, and to prevent injury of any table or support upon which the 90 device may be mounted the under surface of the base 1 may be covered with a layer 51, of felt or other suitable material.

It is thought that the operation of this 95 device will be apparent from the foregoing description. Although only a single form has 100 been shown in which this invention may be embodied, the invention is not limited to any specific construction, but may be applied in various forms without departing from the spirit of the invention or the scope 105 of the appended claims.

Having thus fully described my invention, I claim and desire to protect by Letters Patent of the United States:

1. A cutter, including a fixed member, a 105 blade lever connected to said fixed member to oscillate about a fixed axis, a fixed shearing plate, a blade carried by said lever and slidably engaging said shearing plate and yielding means holding said blade in engagement with said shearing plate, said yielding means being arranged coaxially with the axis of movement of said lever.

2. A cutter, including a blade lever connected to said fixed member to oscillate 110 about a fixed axis, a fixed shearing plate, a blade carried by said lever and slidably engaging said shearing plate and yielding means holding said blade in engagement with said shearing plate, said yielding means 115 being arranged coaxially with the axis of oscillation of said lever, and consisting of a resilient spider interposed between said fixed member and said lever.

3. A cutter, comprising a base, a standard projecting rigidly therefrom, a boss projecting laterally from the upper portion of 120 said standard and having a cylindrical end.

forming with said standard an annular shoulder, a blade lever pivoted to the end of said boss on an axis coaxial therewith, a cutting blade carried by said lever, a shearing plate fixed upon said base and slidably engaged by said blade, and yielding means surrounding said boss and between said shoulder and said lever for holding said

blade in engagement with said shearing plate.

In witness whereof, I have hereunto set my hand this 14th day of June, 1911.

WILBURN N. DENNISON.
